ATTORNEY.

No. 36,819.

Patented February 23, 1904.

UNITED STATES PATENT OFFICE.

FRANK W. LAW, OF PITTSBURG, PENNSYLVANIA.

DESIGN FOR A HEATING-STOVE.

SPECIFICATION forming part of Design No. 36,819, dated February 23, 1904.

Application filed January 8, 1904. Serial No. 188,256. Term of patent 14 years.

To all whom it may concern:

Be it known that I, FRANK W. LAW, a resident of Pittsburgh, in the county of Allegheny and State of Pennsylvania, have invented a new, original, and ornamental Design for Heating-Stoves.

The figure is a perspective view of a heating-stove.

What I claim is—

The ornamental design for a heating-stove, to substantially as shown.

FRANK W. LAW.
